SIGMUND FRIEDMAN, OF GORGONA, CANAL ZONE.

RAIL-TIE.

1,090,041.

Specification of Letters Patent. Patented Mar. 10, 1914.

Application filed January 28, 1913. Serial No. 744,729.

To all whom it may concern:

Be it known that I, SIGMUND FRIEDMAN, a citizen of the United States, and a resident of Gorgona, Canal Zone, Panama, have 5 invented a new and Improved Rail-Tie, of which the following is a full, clear, and exact description.

My invention relates to improvements in railway ties, and means for securing the 10 rails thereto, and the object thereof is to produce a tie which will be so shaped as to obviate all likelihood of the tie moving or working out of place when it is once embedded in the earth, and be provided with a 15 suitable seat by means of which the devices which grip the rail can be firmly fastened in proper position.

Reference is to be had to the accompanying drawings forming a part of this specification, in which the same characters of reference indicate the same parts in all the views.

Figure 1 is a view of one end of my tie showing a rail in section fastened thereto; 25 Fig. 2 is a top plan of the part shown in Fig. 1; Fig. 3 is a sectional view on the line 3—3 of Fig. 2; and Fig. 4 is a perspective view of one part of the rail chair which the tie carries to fasten the rail thereto.

80 The body of my improved tie 1 is preferably made of concrete and is given such a shape as to be trapezoidal in cross-section, with the narrower face serving as the bottom. The rail 2 rests upon the top of this 85 tie at either end, and I employ a reinforcing netting 3 arranged in the form of a tube and extending substantially from one end of the tie to the other to make the tie stronger. The netting of course may extend only a 90 part of the length of the tie, for example, along the middle thereof, or the section between the rails if desired.

The under side of the tie is made concave, as shown at 4, this concave section extending between the rails and serving when the tie is embedded in the ground to prevent the body thereof from moving or working endwise. At the same time, the tapering side of the tie gives a greater bearing surface for tamping and facilitates the removal of the tie from the roadbed.

55 The ends of the tie are provided with transverse recesses 5, and along the corners of these recesses extend undercut ribs 6, to provide a dove-tailed fit for a cushioning block or wood filler 7. This wood filler car-

ries the rail chair 8. This rail chair is made up of a pair of rail braces 9, each of which is cast on a base plate 10, these base plates resting upon the block 7 and being securely 80 fastened to the same.

The base plates 10 have interengaging edges and are bent down along the sides to form ribs 11 having inturned projections 12 which pass under the wood filler 7 and prevent the plates 10 from getting out of position. The bottom of the recess 5 is depressed, as shown at 13, to provide the necessary space between the bottom of this recess and the bottom of the block 7, as will be 70 readily understood.

Each of the plates 10 has a hole 14 in the flange 11, and a lug 15 adjacent the same. It also carries a lug 16, and the edge opposite the flange 11 will be curved as shown at 75 17, to provide recesses and projections which give the interfitting engagement of the plates 10, above mentioned.

The plates 10 are fitted together so as to cause their uneven edges to match, as shown 80 in Fig. 2, and are held in place on the wood filler 7 by means of hook bolts 18. These hook bolts have one end inserted into the holes 14, and will extend across the plates 10 inside the lugs 15 and pass through the 85 perforated ears 16. The ends of these bolts will be threaded to receive nuts to lock the plates 10 together. The braces 9 will have holes 19 to allow the bolts to pass through them. 90

The rail is held in place by means of rail braces 9, one of which is cast upon each of the plates 10, and which are shaped so as to engage the sides of the web 20 of the rail beneath the top and hold it firmly against 95 movement. It will be seen that the lugs 15 will prevent the movement of the adjacent end of the bolts 18 around the apertures 14 as pivots, and thus the rail braces will be held firmly against the rail. 100

The wood filler is dove-tailed into the concrete tie, as stated above, and it may be driven out from either side whenever it is necessary to replace it. It does not bear for its whole length on the tie but only at its 105 ends. This arrangement greatly increases the flexibility of support for the rail chair and allows it to yield when the weight of a train passes over it.

The wire netting reinforcement may be 110 carried as far as the edge of the recess 5, and inverted U-shaped bars may be embed-

ded in the tie at either end beyond the recesses to take up the horizontal thrust along the rail when a train passes over it.

Preferably I construct the plates 10 with 5 interlocking edges, so that the general direction of the recesses and projections on the edges 17 will not be parallel with the tie 2, but slightly diagonal with respect to the same. Consequently, when the plates 10 are 10 drawn together by the hook bolts the plates 10 will not only be drawn to each other across the tie, but will move to some extent in a longitudinal direction, thus forcing the rail braces 9 firmly against the opposite 15 sides of the web of the rail 20. To assist in obtaining this grip on the rail, the hook bolts are preferably placed at a slight angle.

By making the tie proper of concrete I 20 secure an article which is practically inde- structible. Furthermore, the wood filler of- 25 fers a cushion for the rail and makes the tie more resilient than a solid wood tie, thus decreasing the wear on rolling stock and re- ducing the cost of operation.

25 All the parts that are subjected to stress can easily be replaced, and it will be ob- served that no part of the rail chair or any of its fastenings are embedded in the con- crete. The rail chairs or any parts of the 30 same may be removed or replaced without disturbing the rail or the tie either.

The construction of the rail chair dis- 35 tributes the pressure on the head of the rail over a large surface of the tie, this surface being considerably greater than the bottom of the 40 base of the rail. The rail chair gives nu- merous advantages which are not obtained by means of spikes, as it offers a brace on the web of the rail and under the head thereof and prevents springing and breaking of the 45 rail, due to excessive pressure on the side of the rail head. Furthermore, due to the braces 9, all creeping or spreading of the rails will be prevented.

45 Having thus described my invention, I claim as new and desire to secure by Letters Patent:

1. The combination of a tie having a re- 50 cess in one end, a cushioning block secured in said recess, a pair of interengaging plates resting upon said block and having their sides bent over to engage the under side of the block, means for securing said plates together, and locking means carried by each 55 of said plates to engage the sides of a rail and hold the same in position.

2. The combination of a rail having a re- 60 cess in its end, a cushioning block secured in said recess, a pair of plates having interen-

60 gaging edges and having their sides bent over to engage the under face of the block to hold the same in place, a hook bolt secured to the side of each of said plates and extending across the same, lugs carried by said plates to receive the opposite ends of said 65 bolts, means engaging said bolts to hold the same against displacement, and bracing members carried by each of said bolts to engage the sides of a rail beneath the top thereof to hold the same in position. 70

3. A rail chair, including a pair of com- 75 panion members having interengaging edges, each of said members having a side flange which is adapted to lie flush with one side of a tie, and means for securing the members and retaining the same upon the tie. 80

4. A rail chair, including a pair of com- 85 panion rail-engaging members having inter- 90 engaging edges, each of said members hav- ing a side flange which is adapted to be ar- ranged against the side of a tie, inturned pro- 95 jections upon the flanges which enter the sides of the tie, and means for connecting the sections of the chair. 100

5. A rail chair including a pair of com- 105 panion rail brace members, each formed of a casting, and each having interlocking inner 110 edges, each of said members being provided with a side flange which is adapted to lie against one of the faces of the tie, means in- tegrally formed with the side flanges for se- 115 curing the same to the tie, and means for connecting the rail engaging portions of the chairs. 120

6. A rail chair including two interchange- 125 able members each formed of a casting and 130 each comprising a flat base having its outer edge flanged, the base being further formed with a rail brace member which includes 135 spaced sides and a connecting member 140 formed upon the inner edge of one of the 145 said sides, each of the said base portions having its inner edge formed with recesses 150 and projections which are adapted to inter- 155 lock when the sections are assembled upon a 160 tie, means upon the flanges for engaging 165 with the sides of the tie, and means arranged 170 between the sides of one of the rail engaging 175 members and co-acting with the flange of 180 the co-acting member for removably con- 185 necting the sections. 190

In testimony whereof I have signed my name to this specification in the presence of two subscribing witnesses.

SIGMUND FRIEDMAN.
